UNITED STATES PATENT OFFICE.

CHARLES RIENER, OF PHILADELPHIA, PENNSYLVANIA.

OPERATING MECHANISM FOR SIGNALS.

1,240,370.

Specification of Letters Patent. Patented Sept. 18, 1917.

Application filed January 20, 1917. Serial No. 143,419.

To all whom it may concern:

Be it known that I, CHARLES RIENER, a citizen of the United States, residing at Philadelphia, in the county of Philadelphia and State of Pennsylvania, have invented 5 certain new and useful Improvements in Operating Mechanism for Signals, of which the following is a specification.

My invention consists of an improved operating mechanism for signals, one object of 10 the invention being to provide a mechanically operative signaling device including a portion which can be extended beyond the sides of the vehicle to give a signal and can 15 be retracted to its inoperative position after the signal has been given.

Another object is to illuminate said portion of the device so that it will be visible at night.

20 A further object is to so construct my invention that the same means which is operative to project said portion of my invention into a signaling position, is also operative to effect the illumination of said portion 25 when in its projected position.

It is common practice with drivers of vehicles to extend their hand beyond the side of the vehicle as a signal to oncoming vehicles of an intention to turn, slow up, or 30 stop. To signal in this manner requires that the driver remove one of his hands from the steering wheel which often results in the driver losing control of the vehicle. It is therefore one of the important objects of my 35 invention to provide a device which will render the above mentioned manual signaling unnecessary, and I preferably make the above mentioned extensible portion of my invention in the form of a human hand and 40 thereby produce the same general signaling effect as does the manual signaling above referred to.

These objects, and other advantageous ends which will be described hereinafter, I 45 attain in the following manner, reference being had to the accompanying drawings in which—

Figure 1 is a side elevation of my invention showing a casing in section and also 50 illustrating the extensible portion in projected and retracted positions.

Fig. 2 is an enlarged fragmentary sectional elevation of certain of the operative parts illustrated in Fig. 1.

55 Fig. 3 is a section on the line 3—3 of Fig. 2.

Fig. 4 is a face view of electric current controlling means which I employ.

Fig. 5 is a perspective view of a toggle-operating carriage which forms a part of 60 my invention.

Fig. 6 is an enlarged section on the line 6—6 of Fig. 1.

Fig. 7 is an enlarged section on the line 7—7 of Fig. 1. 65

Fig. 8 is an enlarged section on the line 8—8 of Fig. 1.

Fig. 9 is a diagrammatic view of the electric illuminating portion of my invention.

Fig. 10 is a section on the line 10—10 of 70 Fig. 2.

Referring to the drawings, 1 is a casing in which is secured a supporting plate 2, the latter having a yoked upper end providing two parallel plate sections 3 and 4 which are 75 spaced apart to provide a chamber 5. A shaft 6 extends through a hole in the casing 1 and also through holes in a saddle 7. This shaft has an angular portion 8 which is of a length substantially equal to the distance between the legs 9 and 10 of the saddle 7. 80

A hooked cam 11 has one of its ends provided with an angular hole 12 which fits the angular portion 8 of the shaft 6, so that a rotation of said shaft causes the rotation of 85 the cam 11. The lower free end 13 of the cam 11 is designed to move between two rollers 14 and 15 on a carriage 16. This carriage comprises two plates 17 and 18 which are arranged substantially parallel and connected by two short shafts 19 and 20 upon which the rollers 14 and 15 are rotatably mounted. 90

Disks 21 and 22 are also rotatably mounted on the shafts 19 and 20 and arranged at 95 opposite sides of the rollers 14 and 15 for a purpose hereinafter described.

Vertical slots 23 are formed within the plate sections 3 and 4, and the disks 21 and 22 are designed to roll against the edge surfaces produced by said slots 23, the plates 17 and 18 of the carriage being disposed outside of the plate sections 3 and 4. The hooked cam 11 is designed to engage between the rollers 14 and 15 and moves through the 105 chamber 5, for example, from the full line position shown in Fig. 3 to the dot-and-dash line position shown in the same figure. It will thus be understood that a partial rotation of the shaft 6 in opposite directions 110 will produce reciprocation of the carriage 16 longitudinally of the slots 23 or in other

words, the carriage 16 will be raised and lowered. To facilitate this movement, I provide the shaft 6 with a handle 24 as clearly illustrated in Fig. 1.

5 The plate 17 of the carriage 16 is provided with a lug 25 which forms a pivotal connection for the ends 26 of a pair of links 27, the latter forming part of a toggle lever or arm 28. The toggle lever 28 includes a link 29 10 which extends through the pair of links 27 and is pivoted thereto as illustrated at 30. One end of the link 29 is pivoted at 31 to a lug 32 which is secured to the lower end of the plate 2 within the casing 1. The link 29 15 at its other end is pivoted between a pair of links 33, and the pair of links 27 has a single link 34 pivotally connected therewith, the single link 34 extending between the two links of the pair 33 and is pivoted thereto 20 at 35.

In the same manner, another pair of links 36 are pivotally connected to the link 34, and a link 37 is pivotally connected between the pair of links 33 and the pair 36. Each of 25 the links of the pair 36 and the link 37 have end links 38 pivotally connected thereto and to each other as shown at 39. A bar 40 is secured to the upper of the links 38 and to a signaling member 41. It will thus be noted 30 that the links above described form a toggle lever which, when the carriage 16 is raised, will be retracted into the dot-and-dash line position shown in Figs. 1 and 2, and with it 35 the member 41.

35 On the other hand, when the carriage 16 is lowered, the toggle lever will be extended into the position shown in full lines in Figs. 1 and 2. The member 41 is preferably made 40 of metal and in the form of a human hand, and comprises two main sections 42 and 43.

The sections 42 and 43 provide a chamber 44 and are hinged together at their top edges 45 as shown at 45 and provided with a clip 46 at their lower edges to keep the sections closed under operative conditions. Each of 50 the sections has extensions 47 which combine to form the fingers of the hand, and these sections 47 are spaced apart as shown at 48, so that light from an electric lamp 49 which 55 is within the chamber 44, will shine through and be visible through the spaces between the fingers or between the sections 47.

The lamp 49 may be of any of the usual 55 form of electric bulbs, and its socket 50 is held within a spring clamp 51 which is secured to the section 42. The bar 40 is also secured to the section 42, so that the section 43 is free to open on the hinge 45 to permit access to the lamp 49. The section 43 is also 60 provided with a hole 52 which is directly in register with the lamp 49 (see Fig. 1).

The means which is operative to illuminate the lamp 49 when the member 41 is extended, consists of the following elements:—A recessed collar 53 is secured to

the inner end of the shaft 6 by means of a set screw 54. An insulating sleeve 55 has a hole through which the said inner end of the shaft extends and also has a portion 56 which fits within the recess of the collar 53, 70 the set screw 54 passing through the portion 56 of the insulating sleeve as clearly shown in Fig. 2.

The outer end of the sleeve 55 is elliptical in shape as shown in Fig. 4, and is provided with a metallic band 57 preferably made of copper or other material which is a good conductor of electricity.

Two metallic brushes or switch arms 58 and 59 are free at their upper ends and extend at opposite sides of the inner end of the shaft 56. These ends are normally of a greater distance apart than the minor axis of the elliptical band 57 and of less distance apart than the major axis of said elliptical band. For example, when the band is in the position shown in Fig. 4, it contacts with both of the brushes 58 and 59, however, when turned in a position at right angles to the position of this figure, 80 the brushes 58 and 59 will be out of contact with the band, such a position being shown in dot-and-dash lines in Fig. 3.

The lower ends of the brushes 58 and 59 are supported by an insulating block 60 95 which in turn is carried by a bracket 61 secured to the leg 9 of the saddle 7 (see Figs. 1 and 2). The block 60 has a concaved upper surface 62 against which fits a clamping plate 63, the latter being secured by 100 screws 64 to the bracket 61. This forms a rigid support for the insulating block 60 and the brushes 58 and 59.

The links of the toggle lever 28 are provided with eyelets 65 which form guideways for the wire 66 which leads to the lamp 49, said wire being extended to a battery (not illustrated) and branches of the wire being connected to the respective brushes 58 and 59 so that when the elliptical band 57 is in the position illustrated in Fig. 4, the electric circuit will be closed and current will be supplied to the lamp 49 to illuminate the same.

It will be noted that the insulating sleeve 55, band 57, and carriage 16 are so positioned that when the shaft 6 is turned to effect the lowering of the carriage 16, to extend the member 41, the band 57 will be moved to contact with the brushes 58 and 59 and thereby illuminate the lamp when the member 41 is extended. On the other hand, when the shaft 6 is turned in an opposite direction to effect the raising of the carriage 16, and to retract the member 41, the band 57 will be moved out of contact with the brushes 58 and 59 and the lamp 49 will be extinguished.

As illustrated in Fig. 10, each of the pivotal connections between the links of the

toggle lever 28 are formed to include a ring 67 which is fitted within a hole 68 in the link which is intermediate the links of the port to which it is connected. The pin 69 forming the pivot between the links, extends directly through said ring, and through the links of the pair which are arranged at opposite sides of the intermediate link. By this construction, friction between the links 5 of the toggle lever is reduced to a minimum, since the rings 67 form extended bearings 10 for the pivotal connections.

In the use of my invention, it is only necessary for the operator or driver of a vehicle to move the handle 24 a quarter of a turn to effect the extension of the member 41 to give the signal, and upon the return of the handle 24 to its original position, the member 41 will be retracted.

20 The casing 1 may be secured in any suitable manner to the vehicle and the handle 24 may be located directly adjacent the steering wheel, so that it will require but a small movement of one of the driver's hands to 25 actuate the handle 24 and thereby produce the signal.

While I have described my invention as taking a particular form, it will be understood that the various parts of my invention 30 may be changed without departing from the spirit thereof, and hence I do not limit myself to the precise construction set forth, but consider that I am at liberty to make such changes and alterations as fairly come within 35 the scope of the appended claims.

Having thus described my invention, what I claim as new and desire to secure by Letters Patent is:

1. The combination with a member, a 40 lever supporting said member, means forming a slotted slideway, a carriage having anti-friction rollers thereon movable in said slideway and for engagement with the opposite walls thereof, said carriage being secured to certain of the links of the toggle 45 lever, and means for moving said carriage to effect pivotal movement to the links of the toggle lever and thereby cause said member to be extended and retracted, substantially as described.

2. The combination with a member, a lever supporting said member, means forming a slotted slideway, a carriage having anti-friction rollers thereon movable in said 55 slideway and for engagement with the opposite walls thereof, said carriage being secured to certain of the links of the toggle lever, and a cam for moving said carriage, said cam being designed to engage against certain of the anti-friction rollers, substantially as described.

3. The combination of a member, a toggle lever supporting said member, a supporting structure, means for pivoting one 60 of the links of said toggle to the supporting

structure, means providing a slideway, a carriage pivotally connected to another of the links of the toggle lever, and a cam operative to reciprocate said carriage, substantially as described.

4. The combination of a member, a toggle lever supporting said member, a supporting structure, means for pivoting one of the links of said toggle to the supporting structure, said supporting structure having 70 a guide-way formed therein, a carriage slideable within the guide-way and having means spaced apart, said carriage being pivotally connected to another of the links of the toggle lever, and a cam operative to move 75 between said latter means to effect the movement of said carriage within said guide-way whereby the member is extended and retracted by the toggle lever, substantially as described.

5. The combination of a member, a toggle lever supporting said member, a supporting structure including two sections spaced apart, a carriage including plates designed to slide at opposite faces of said sections of the supporting structure, shafts connecting said plates, rollers on said shaft and extending between said sections of the supporting structure, said sections of the supporting structure having slots therein 95 forming guide-ways and through which said shafts extend, a cam for engagement between said rollers of the carriage, a shaft operatively connected to said cam, a handle on said shaft, means forming a pivotal connection between the carriage and one of the links of the toggle lever, and means forming a pivotal connection between said supporting structure and another of the links of said toggle lever, substantially as described. 100

6. The combination of a member, a toggle lever supporting said member, a supporting structure including two sections spaced apart, a carriage including plates designed to slide at opposite faces of said 110 sections of the supporting structure, shafts connecting said plates, rollers on said shaft and extending between said sections of the supporting structure, said sections of the supporting structure having slots therein 115 forming guide-ways and through which said shafts extend, a cam for engagement between said rollers of the carriage, a shaft operatively connected to said cam, a handle on said shaft, means forming a pivotal connection between the carriage and one of the links of the toggle lever, means forming a pivotal connection between said supporting structure and another of the links of said toggle lever, and disks on said first-mentioned shafts for engagement with the edge surfaces of said supporting structure forming said slotted guide-ways, substantially as described.

7. A toggle lever including links pivoted 120

together, certain of said links being arranged in pairs with a connecting link interposed between them, and rings surrounding the pivots for said links and interposed between the links of the pairs, substantially as described.

In testimony whereof I have signed my

name to this specification in the presence of two subscribing witnesses.

CHARLES RIENER.
